SLIDING WINDOW SCREEN SUPPORTING
STRUCTURE

Emil Gutoski, Cicero, Ill.

Application October 28, 1944, Serial No. 560,788

3 Claims. (Cl. 160—369)

1

My invention relates to sliding screens for windows and particularly to improved arrangement for co-operation of the screen sash with guide rails on the window frame for preventing accidental outward displacement of the screen from the guide rails and falling of the screen out of the window frame.

A usual way of fitting screens to wooden window frames is to nail guide strips or rails to the sides of the window frame, and to provide grooves in the side edges of the screen sash for receiving the rails so that the screen may be readily slid vertically on the rails for support in the window frame or to be withdrawn therefrom. It frequently happens that when the screens are to be applied to the windows of a house at the beginning of a summer season, the screens will not all be reapplied to the respective window frames for which they were originally fitted. Sometimes a screen which is somewhat narrower than the right screen for a window frame is inadvertently applied to the window frame. Under such conditions the guide strips on that window frame may not afford sufficient abutment at all times to prevent accidental outward displacement of the sash from the window frame, and it has frequently happened that an improperly supported screen has been subjected to accidental outward pressure by a child leaning thereagainst resulting in release of the screen from the rails and falling of the child out of the window.

Heretofore the guide strip or rail usually used was of T-shaped cross section, that is, comprising a rectangular base for seating against the side of the window frame and with the leg or guide bead extending inwardly to receive the groove in the edge of the screen sash. However, in such grooved screens heretofore used, the width of the screen at opposite sides of the grooves was the same, that is, the tongues at opposite sides of the grooves were of equal width. Therefore when a screen which was not of the proper width was inadvertently applied to the guides in a frame, lateral edgewise displacement of the screen in the frame would bring the edge of the inside tongue of the screen close to or outside of the usually rounded end of the guide bead so that comparatively very little outward pressure against the screen would result in outward displacement of the screen from the frame.

In accordance with my invention I provide guide strips of L-shaped cross section and secure the guides to the sides of the window frame with their base portions extending outwardly, and with the width of the screen at the inner side

5 of the grooves wider than the outer portion outside of the grooves so that, if the particular screen which had been fitted for a particular window were replaced by a screen of narrower width, the comparatively wide inner tongues of the sash will maintain extended contact with the guide rails to hold the screen against accidental outward displacement from the window by pressure against the inside thereof.

10 My invention will be fully understood by reference to the drawing, in which:

Figure 1 is a front elevation of a window structure on which my improved screen supporting arrangement is applied;

15 Figure 2 is an enlarged perspective view of a portion of the side rail of a screen sash;

Figure 3 is a perspective view of a portion of a guide rail;

20 Figure 4 is an enlarged section on plane IV—IV Figure 1; and

Figure 5 is a cross-sectional view showing the prior art type of guide rail and sash over which my invention is an improvement.

25 Referring first to Figure 5, I have shown a type of guide strip which has been in common use. This strip is usually of wood and of T-shaped cross section, comprising the rectangular base 10 with the guide leg or bead 11 extending therefrom, the strip being secured to the sides 30 of a window frame usually by nailing. The side walls 12 of the wooden sash of the screen were heretofore provided with the longitudinally extending grooves 13 but with the inner and outer tongue portions 14 and 15 at opposite sides of the grooves of equal width. When a sash is fitted for a particular window, the inner and outer tongue portions 14 and 15 will engage with the base portion 10 of the guides at opposite sides of the beads 11. However, it frequently 35 happens that, when the screens for a house are installed at the beginning of a summer season, the screen originally dimensioned for a certain window will not be installed, but a screen for some other window and which is of less width, will be installed. Now, should this wrong screen become displaced laterally edgewise in the window frame with one edge against the rail at one side of the frame, then, as shown on Figure 5, the ends of the tongues at the other edge of the screen may be so far displaced from the base 40 10 of the guide strip that the inner edge of the inner tongue 14 will be close to the usually rounded end of the bead 11 so that any abnormal pressure outwardly against the screen would cause 45 it to swing out away from the guide strip and

fall out of the window frame. This wrongful installing of screens in window frames has frequently resulted in accidents, as children climbing onto the sill of the window, or leaning out over the sill, may exert pressure against the screen which will readily give under such pressure and together with the child will fall out of the window frame.

Figure 1 shows a window to which my improved guides and sash have been applied, the screen S being in the lower part of the window frame 10 to close down against the sill 16.

Referring to Figure 4, the lower window sash 17 is vertically slidable between the side walls 18 of the window frame under guidance of outer 15 and inner strips 19 and 20. The screen S is applied to the opening 21 between the side walls 22 of the casing forming the outer side of the window framework.

Instead of using guide strips of T-shaped cross section, as shown on Figure 5, I use guide strips of L-shaped cross section comprising the base 23 and the guide leg or bead 24 extending therefrom. The guide strips are secured, as by nails 25, to the inner edges of the casing boards 22 with the base legs 23 extending outwardly, as shown on Figure 4.

The side members 26 of the screen sash have the longitudinally extending grooves 27 in their outer edges for receiving the guide beads or legs 24 of the guide strips, with the inner and outer tongues 28, 29 at opposite sides of the grooves engaging with the inner and outer sides of the guide strips. When the screen sash is made for a certain window frame, the width of the sash will be made such that the ends of the inner tongue 28 will engage with the inner edges of the casing boards 22, and the outer tongue 29 will engage with the base portions 23 of the guide strips, as shown at the right of Figure 4. Thus, when a sash has been originally fitted into a certain window frame or is reapplied to the same window frame after removal thereof, the wide inner tongues 28 of the sash will be in engagement with the inner side of the base portions 23 of the guide strips as well as the inner side of the guide strip legs or beads 24, while the narrower outer tongues will be in engagement only with the outer sides of the guide strip beads. With this comparatively long extent of engagement of the inner tongues 28 with the guide strips, screen sashes of less width than the sash originally fitted for a certain window frame may be applied to such frame without danger of outward displacement of the sash from the window frame, as the wide inner tongues 28 will maintain sufficient extent of engagement with the guide strips to prevent such outward displacement. Figure 4 shows the application to a window frame of a screen sash whose width is considerably less than the width of the sash originally fitted for such window frame. The inserted sash, even if shifted edgewise to one side of the opening 21, will maintain sufficiently extended engagement of the tongue 28 at the other edge with the corresponding guide strip to prevent outward displacement of the screen sash from the window frame. As shown on Figure 4, the screen sash outer tongue 29 at the left edge thereof might permit inward swing of the screen sash, but the corresponding inner tongue 28 will be in extended abutting engagement with the corresponding guide strip to prevent outward swing of the screen sash. Thus, even though a screen sash of less width than that for a certain window frame be inadvertently in-

stalled in such frame, the screen sash will be held against outward displacement under pressure against the inside thereof, this resulting in avoidance of accidents which might otherwise occur, as for example, with guide strip arrangement heretofore used and shown on Figure 5.

I have thus produced an improved interconnection between a sash and a window frame which will hold a sash against outward displacement from the window frame even though the width of the inserted sash is considerably less than that of the sash intended for such window frame. My improved interconnection may be installed without any increase in cost over that of prior interconnections such as have been referred to hereinbefore.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. Interconnection between a sliding sash and a window frame comprising guide strips of L-shaped cross section secured to the sides of the window frame with their base legs thereagainst and with their other legs extending inwardly from the inner ends of the base legs to provide guide beads, and providing a strip with a sash bearing surface which is the thickness of the strip base plus the thickness of the other leg, longitudinally extending grooves in the respective side edges of the sash for receiving said guide beads, the sash at the inner side of said grooves being of a width substantially equal to the distance between the walls of the frame to which said guide strips are secured, and the width of the sash at the outer side of said grooves being substantially equal to the distance between the base legs of the guide strips, whereby extended abutment engagement will be maintained between said guide strips and the sash at the inner side of said grooves for preventing outward displacement of the sash from the window frame under pressure against the inner side thereof.

2. An interconnection between a sliding sash and a window frame comprising guide strips of L-shaped cross section respectively secured to the opposite side walls of the frame with their base legs thereagainst and with their other legs at the inner ends of the base legs extending toward each other to provide guide beads and providing a strip with a sash bearing surface which is the thickness of the strip plus the thickness of the other leg, the opposite edges of the sash being cut to provide guide grooves for receiving said guide beads and to leave short guide tongues at the outer side of said grooves for engaging with the outer sides of the guide beads and longer guide tongues at the inner side of the grooves for engaging with the inner side of the base and guide bead of said guide strips throughout the strip bearing surfaces, whereby extended abutment engagement is maintained between said long tongues and said guide strips upon lateral edgewise shift of said sash away from either of said guide strips and outward displacement of the sash from the frame under pressure against the inner side of the sash will be prevented.

3. In the combination of a window frame and a sliding screen, guide strips of L-shape fastened to the side walls of the frame along their outer margins with the bases of the strips towards the

outer wall margins and the beads extending at right angles to the side walls, said strips providing inner screen sash bearing surfaces which include the cross-sectional thickness of the bases plus the inner side surfaces of the beads, the side rails of the sash having grooves forming spaced tongues from top to bottom thereof for engaging the strip beads, the tongues engaging with the inner bearing surfaces of the strips being of substantially the same width as the said surfaces 10

and the tongues engaging with the outer bearing surfaces of the strip beads being substantially the same width as the outer surface of the beads, whereby abutment engagement is maintained between the inner tongues and the guide strips during lateral shift of the sash in said frame to thereby prevent outward displacement of the sash from said frame under pressure against the inner sides of the same.

EMIL GUTOSKI.
